UNITED STATES PATENT OFFICE.

HENRY L. BRUEN, OF ORANGE, NEW JERSEY, AND EDWIN B. GROSS, OF THOMASTON,
CONNECTICUT.

DESIGN FOR AN ATOMIZER NOZZLE.

Application filed June 29, 1923. Serial No. 6,623. Term of patent $3\frac{1}{2}$ years.

To all whom it may concern:

Be it known that we, HENRY L. BRUEN and EDWIN B. GROSS, citizens of the United States, residing, respectively, at Orange, New Jersey, and Thomaston, Connecticut, have invented a new, original, and ornamental Design for Atomizer Nozzles, of which the following is a specification, reference being had to the accompanying drawings, forming part thereof.

The figure is a perspective view of an atomizer nozzle showing our new design.

We claim:

The ornamental design for an atomizer nozzle as shown.

HENRY L. BRUEN.
EDWIN B. GROSS.
